UNITED STATES PATENT OFFICE

LOUIS B. WEIL, OF CHICAGO, ILLINOIS

DESIGN FOR A COSMETIC JAR

Application filed December 13, 1930. Serial No. 37,964. Term of patent 3½ years.

To all whom it may concern:

Be it known that I, LOUIS B. WEIL, a citizen of the United States, and resident of Chicago, in the county of Cook and State of Illinois, have invented a new, original, and ornamental Design for a Cosmetic Jar, of which the following is a specification, reference being had to the accompanying drawings, forming part thereof.

I claim:
The ornamental design for a cosmetic jar as shown.

LOUIS B. WEIL.
